BEAM COMPASS

John W. Oehrli, State College, Pa.

Application June 13, 1944, Serial No. 540,158

10 Claims.

This invention relates to beam compasses, and particularly to beam instruments having a movable trammel provided with a tilting control.

It has been recognized that in many instances there is a degree of resilience and lack of rigidity in bow compasses and the like that make a beam compass an essential for certain uses. With this latter form of compass, however, successful use has been circumscribed by the fact that with a sliding bodily movable trammel point or the like, only rough adjustments can be made, while delicate, substantially micrometric adjustments are necessary but have not been provided and are not readily secured. When adjustments of refinement have been added to the control over the bodily trammel movement according to past practices, the instruments have been complicated, expensive, difficult to adjust, subject to undue wear making for inaccuracies, and possessed of such degree of resilience as to militate against the complete accuracy essential for proper use of the instruments.

It is among the objects of this invention; to provide a beam compass with a bodily movable trammel and separate means for securing minutely incremental exact and facile tilting control of the trammel point; to simplify the construction of beam compasses; to provide a simple form of tilting control for a beam compass trammel; to provide a rotatable cam cooperating with a fulcrum on opposite sides of a beam for securing exact and relatively fixed tilting adjustments of the trammel relative to the beam, which adjustment is maintained until manually changed by the operator; to provide a trammel with three points of gripping engagement of a beam which are arranged for adjustment for securing tilting control while maintaining substantially constant grip on the beam; and many other advantages and objects of the invention will become more apparent as the description proceeds.

In the accompanying drawings forming part of this description:

Fig. 1 represents a side elevation of a beam compass constructed in accordance with one form of the invention, showing in respectively full and dotted lines two different positions of a trammel point in its tilting relation to the beam.

Fig. 2 represents a side elevation of the tilting sliding trammel of this invention mounted on a beam, taken looking along the beam, according to the preferred form of invention.

Fig. 3 represents a longitudinal axial section of the tilting sliding trammel and beam of Fig. 2, taken transversely thereof, in a mid-position of

(Cl. 33—160)

perpendicularity relative to the beam, with the beam in merely fragmentary section, and indicating in dotted lines the relative beam position in a position of relative tilting of the trammel on the beam.

Fig. 4 represents a fragmentary section through the elevation of Fig. 2 on line 4—4 thereof, on an exaggerated scale.

Fig. 5 represents a fragmentary elevation of a detail of the upper end of a trammel according to the preferred form of invention.

Fig. 6 represents a plan of the fragment of trammel shown in Fig. 5.

Fig. 7 represents a side elevation of a pivoted sliding trammel according to a modified form thereof, looking into the beam-receiving opening thereof.

Fig. 8 represents a longitudinal section through the modified form of sliding tilting trammel shown in Fig. 7 with a fragment of beam shown in full lines in one relatively adjusted tilting position of the beam and trammel.

In the preferred form of invention, shown in Figs. 1 and 2 and in detail in Fig. 3, a beam 10 is provided which is preferably substantially rectangular in cross section, having lateral parallel walls or surfaces 11 and 12, and upper and lower walls or surfaces respectively 13 and 14, and illustratively may be comprised of a deformed tube, although if desired a solid rod may be used. Preferably, the corners of the beam are slightly rounded instead of being completely sharply angular. In the beam shown in Fig. 1, a reduced end 15 is formed for resilient interlock with an adjacent section of beam, if appreciable length greater than one beam is required. Usually the compass will include two or three different lengths of beam, including a very short one for small arcs. On this beam 10, when used as a compass, there are preferably two trammels, respectively, a primary trammel 16, and a secondary trammel 18.

Primary trammel 16 is preferably of such length as to furnish a grip for the fingers and comprises preferably a mere trammel point 17 to be located at the center of rotation. Secondary trammel 18 is preferably rather short and carries the marking element, whether it be another point, a pen, or the pencil point 20 shown in Figs. 1, 2 and 3. It will be understood that in using the beam compass the trammels are suitably apertured as will be described and the leg or trammel 16 is first mounted on the beam at a convenient point toward one end thereof, and is preferably held tightly against undesired movement, and the secondary trammel 18 is mounted and slid along the

beam in a position of perpendicularity thereon, preferably, until the point or lead 20 is approximately on the mark for the desired arc. Then all sliding stops, because such bodily trammel movement is not sufficiently certain and delicate and needs to be sharpened by the substantially vernier movement incident to tilting in accordance with the invention. When the sliding stops with the secondary trammel approximately near the mark, then it is tilted as to bring the point 20 exactly on the mark. In moving through a succession of very close marks, tilting the secondary trammel can take care of the most minute changes.

In the preferred form of tilting trammel of either primary trammel 16 or secondary trammel 18, a single tubular member 21 is provided having the transverse through aperture 22 formed with the axial parallel side edges 23 and 24 arranged for close sliding fit with the parallel side walls 11 and 12 of the rectangular beam 10 to prevent wobble or oscillation about the longitudinal median axis of the beam 10, while the upper and lower surfaces of the slot have clearance from beam surfaces 13 and 14. Below the aperture 22, the tube 21 terminates in a skirt 25 to receive with a tight push fit, the mechanism to be described. A pencil lead or point chuck element 26 at the inner end is flared to form the hollow cylindrical portion 27 arranged for anchored engagement within the skirt 25 of the main tube. Preferably, a mere tight machine fit will suffice to prevent relative motion between these parts, although if desired they may be spot-welded or otherwise tacked together. The cylindrical end part of the chuck has an external shoulder 28 under the skirt 25, and is threaded as at 30 to receive the compression collet 31 which constricts the lower portion of the chuck against the lead 20. The space within the cylindrical portion 27 houses a compression spring 32 working within the inner periphery of a tubular extension 33 of a spring-pressed conical follower fulcrum point 34 having the axial aperture 35. The spring pressed conical fulcrum has an outer periphery 36 slidably guided in the skirt 25 below the transverse slot or beam opening 22, and the spring 32 bears against the fixed internal shoulder 37 of the chuck and the inner shoulder formed by the conical end 34 to urge the spring pressed fulcrum axially toward the transverse slot 22 and into contact with the lower surface 14 of the beam 10 when the latter is in the slot 22. Preferably, the tube 21 is indented to form an internal bulge or stop, not shown, for limiting the outward axial movement of the spring pressed fulcrum plunger 34. Above the upper limits of the slot 22, a ring 38 is anchored immovably on the tube 21, in any desired manner, as by welding or brazing or the like, and the lower surface thereof as at 40 lies in a substantial plane normal to the longitudinal axis of the trammel tube 21. An annular cam 41 is mounted on tube 21 and has an upper surface 42 in a plane normal to the axis of the cam and of the tube but has a lower planar cam surface 43 lying in a plane angularly divergent from the perpendicular of the axis of the cam so as to have a high point 45 and a low point 46 in said plane 43. The cam is provided with an internal bore 44 such as to engage and rotate readily on the outer surface of the tube 21 in guided engagement with the fixed ring 38 so that the cam surface 43 changes its position so that its diametrically spaced high point 45 and low point 46 can reverse or assume any desired diametrical complemental

position. Preferably, as a simple means to prevent the cam 41 from dropping axially away from fixed abutment 38, its inner periphery 44 has a central peripheral groove 47 into which a small bump 48 can be forced by a small tool directed through slot 22 before association of the beam 10 therewith.

With the parts as thus far described, it will be clear that the secondary trammel 18 can be threaded easily upon the end of the beam 10, as it simply requires a slight axial depression of the spring plunger to suitably position the trammel and the beam. Note that the spring pressed plunger 34 exerts friction on the lower surface 14 of the beam, and also forces the upper surface 13 thereof against two substantially diametrically spaced points on cam surface 43, and establishes a frictional contact between the cam surface and the beam. With the cam turned so that the center of the high point 45 extends radially of the tube 21 transversely of the beam, it will be clear that the trammel 18 will be disposed perpendicularly upon the beam as the upper surface 13 thereof will engage two symmetrically disposed points on the cam surface 43. It will remain in such perpendicular relation due to the frictional constraint of the spring pressed plunger although still permitting predetermined sliding movements of the whole trammel bodily along the beam. This is for the "rough" adjustment, so to speak. For making the final adjustment or for making progressive changes in the location of the point 20 in the plane of the beam, the operator's fingers very readily grasp the knurled edge of the cam 41 and rotate same in either direction required so as to move the high point 45 toward one side or the other of the former mid-position transverse of the beam, to displace the symmetrical point engagement and establish asymmetrical point engagement between the beam and cam surface relative to the perpendicular of the axis of tube 21, to gradually force the angular relation of the beam and trammel to change. It will be clear that this will be accomplished by simultaneously moving the wide portion of the cam to lie between the beam and the fixed planar guide surface 49 of the stop ring 38 on one side or the other of the neutral perpendicular relation, while also simultaneously moving the thinner portion of the cam between low point 46 and the guiding planar surface 49 of the fixed abutment on the other side of the neutral perpendicular relation, to maintain constant and uniform compensatory pressure on the beam on each side of the fulcrum point. This establishes consequently an ability to locate the point 20 anywhere in a wide swing on each side of the neutral mid-position, varying in size in accordance with the steepness of the cam, among other limitative factors. It will be clear that the pressure on the spring-pressed plunger will be a little greater at extreme tilting positions of the cam, but this is very simple, as the spring just yields that required amount. The simplicity, utility and economy of the construction so far described will be obvious.

It will be understood that both trammels may be of the same construction if desired, and thereby very close disposition of the axial point and the arc-marking device will be facilitated. For certain purposes, however, it may be desirable to provide the form of device shown in Fig. 1, at 16, in which the tube 21, otherwise identical with trammel 18 of Fig. 3, is prolonged, is flattened as at 49, and the end may be closed or left open, and preferably it is knurled. The purpose in leaving

tube 21 open, at least far enough to permit the passage of a wire, is so that with the beam withdrawn, the wire can be forced into the aperture 35 to force out any pieces of broken lead that may have lodged in the chuck assembly.

It will be clear that the combination of elements on opposite sides of the beam comprising a fulcrum on one side of the beam in line with the axis, and the high and low points of the cam on the other side of the beam and of the axis of the tube of the fulcrum, furnishing a three-point grip of the trammel on the beam in all positions of adjustment for tilting, can find expression in other forms than the particular species disclosed in Fig. 3. For an illustrative modification incorporating the same control principle, reference may be made to the disclosure of Figs. 7 and 8. In this form, a shaft, illustratively relatively solid, as at 50, at the lower end terminates in a lead or point-gripping chuck element as 51, carrying the threaded rotatable collet member 52 for tightening and controlling the grip on an illustratively combined point and lead 53. The shaft is axially and transversely bored as at 54 to removably house the inner end of the combined element 53, and is provided with a transverse beam-receiving bore 55 having the bottom sloping surfaces meeting or merging in the fulcrum ridges or knife edges 56 transversely formed by curved spaced shoulders or effective fulcrums at 57 and 58, upon which the corners formed by the intersection of the side walls 11 and 12 with the lower surface 14 of the beam 10, rock in response to rolling change of pressure from the cam to be described. The vertical extent of the slot 55 is such as to receive and permit swinging of the beam to permit tilting of the trammel relative to the beam. The upper end of the body 50 is preferably tubular for lightness and is provided with the short axial recess 60 to receive the anchoring tongue 61 on the spring washer 62 forming the bearing surface for the cam to be described, and which in turn is adjustably forced against said cam by the knurled nut 63. A cam 64 having an upper planar surface 65 normal to the axis of the cam is mounted rotatably on the tubular extension of the body 50, with the upper guide plane in engagement with opposite convolutions of the spring washer 62, and with the planar cocked cam face 66 overhanging the upper end of the transverse slot 55 with the high side 67 and low side 68 arranged to engage the beam 10 and swing the beam and trammel relatively on the fulcrums 57 and 58, as in the preferred form. It will be evident, however, that in the instant form, the tension of the spring and, therefore, the frictional effect can be varied by rotation of the knurled nut 63. The tension on the spring washer imparted by the nut 63 is a means for regulating the slidability and also the tilting ability of the trammel. With one tension the trammel slides freely and adjusts the same in tilting, but it may not be sufficiently fixed. It is perfectly possible to make the sliding bodily adjustment, then the tilting adjustment, before tightening the nut 64 and therefore tightening the friction spring washer, although it is preferred to establish a degree of spring tension such as to permit restrained sliding, while permitting restrained but facile tilt adjustment. It will be observed that in moving from the mid-position of no tilt toward tilt in either direction, the line from the fulcrums 57 and 58 to the upper surface is very slightly increased. This may be desirable as it increases the friction toward the extremes of tilting while markedly diminishing it in the mid-

position. This serves as an indication of trammel position and angle that is sometimes beneficial.

Having thus described my invention, I claim:

1. In beam compasses, a trammel having a beam-receiving aperture with parallel lateral walls, a beam having parallel side walls arranged to be received in said aperture and to have a sliding engagement with the said parallel walls to prevent relative rotation of the trammel or beam respectively about its longitudinal axis, said aperture having vertical clearance to permit relative swinging of the trammel and beam in the plane median of the two parallel walls, and means in the trammel engaging the upper and lower surfaces of the beam for adjusting the relative angular positions of the beam and trammel in said median plane, said means comprising a rotatable cam mounted with its axis concentric with the axis of the trammel and having a sloping surface arranged to engage one of the surfaces of the beam.

2. In beam compasses, a trammel having a beam-receiving aperture with parallel lateral walls, a beam having parallel side walls arranged to be received in said aperture and to have a sliding engagement with the said parallel walls to prevent relative rotation of the trammel or beam respectively about its longitudinal axis, said aperture having vertical clearance to permit relative swinging of the trammel and beam in the plane median of the two parallel walls, means in the trammel engaging the upper and lower surfaces of the beam for adjusting the relative angular positions of the beam and trammel in said median plane, said means comprising a rotatable cam mounted with its axis concentric with the axis of the trammel and having a sloping surface arranged to engage one of the surfaces of the beam, and fulcrum means on the opposite side of and in contact with the beam from the cam means with reference to which the beam and trammel effectively tilt as the cam is rotated.

3. In beam compasses, a trammel having a beam-receiving aperture with parallel lateral walls, a beam having parallel side walls arranged to be received in said aperture and to have a sliding engagement with the said parallel walls to prevent relative rotation of the trammel or beam respectively about its longitudinal axis, said aperture having vertical clearance to permit relative swinging of the trammel and beam in the plane median of the two parallel walls, means in the trammel engaging the upper and lower surfaces of the beam for adjusting the relative angular positions of the beam and trammel in said median plane, said means comprising a rotatable cam mounted with its axis concentric with the axis of the trammel and having a sloping surface arranged to engage one of the surfaces of the beam, fulcrum means on the opposite side of and in contact with the beam from the cam means with reference to which the beam and trammel effectively tilt as the cam is rotated, and resilient means for urging the fulcrum and cam surfaces into relative gripping engagement of said beam.

4. In beam compasses, a trammel having a beam-receiving aperture with parallel lateral walls, a beam having parallel side walls arranged to be received in said aperture and to have a sliding engagement with the said parallel walls to prevent relative rotation of the trammel or beam respectively about its longitudinal axis, said aperture having vertical clearance to permit relative swinging of the trammel and beam in the plane

median of the two parallel walls, means in the trammel engaging the upper and lower surfaces of the beam for adjusting the relative angular positions of the beam and trammel in said median plane, said means comprising a rotatable cam mounted with its axis concentric with the axis of the trammel and having a sloping surface arranged to engage one of the surfaces of the beam, fulcrum means on the opposite side of and in contact with the beam from the cam means with reference to which the beam and trammel effectively tilt as the cam is rotated, and resilient means for urging the fulcrum and cam surfaces into relative gripping engagement of said beam, said resilient means effective on the fulcrum point to permit yielding thereof.

5. In beam compasses, a trammel having a beam-receiving aperture with parallel lateral walls, a beam having parallel side walls arranged to be received in said aperture and to have a sliding engagement with the said parallel walls to prevent relative rotation of the trammel or beam respectively about its longitudinal axis, said aperture having vertical clearance to permit relative swinging of the trammel and beam in the plane median of the two parallel walls, means in the trammel engaging the upper and lower surfaces of the beam for adjusting the relative angular positions of the beam and trammel in said median plane, said means comprising a rotatable cam mounted with its axis concentric with the axis of the trammel and having a sloping surface arranged to engage one of the surfaces of the beam, fulcrum means on the opposite side of and in contact with the beam from the cam means with reference to which the beam and trammel effectively tilt as the cam is rotated, and resilient means for urging the fulcrum and cam surfaces into relative gripping engagement of said beam, said resilient means effective on the cam means to cause it to frictionally engage the beam.

6. In beam compasses, a trammel having a beam-receiving aperture with parallel lateral walls, a beam having parallel side walls arranged to be received in said aperture and to have a sliding engagement with the said parallel walls to prevent relative rotation of the trammel or beam respectively about its longitudinal axis, said aperture having vertical clearance to permit relative swinging of the trammel and beam in the plane median of the two parallel walls, means in the trammel engaging the upper and lower surfaces of the beam for adjusting the relative angular positions of the beam and trammel in said median plane, said means comprising a rotatable cam mounted with its axis concentric with the axis of the trammel and having a sloping surface arranged to engage one of the surfaces of the beam, fulcrum means on the opposite side of and in contact with the beam from the cam means with reference to which the beam and trammel effectively tilt as the cam is rotated, resilient means for urging the fulcrum and cam surfaces into relative

gripping engagement of said beam, said resilient means effective on the cam means to cause it to frictionally engage the beam, and means adjustable to vary the tension of the said resilient means.

7. A beam compass comprising a beam, a trammel having a beam aperture to enable sliding of the trammel on the beam, fulcrum means on the trammel engaging one side of the beam, cam means on the trammel engaging the beam on a side opposite to that engaged by the fulcrum and establishing with the fulcrum a substantial triangle of beam-gripping substantial points, and a single means operable to swing the thus created triangle gripping means from a position of symmetry with the axis of the trammel to positions of asymmetry therewith to adjust the trammel in a plane containing the beam and trammel.

8. In beam compasses, a trammel having a beam-receiving aperture, a beam positionable in the aperture, means on one side of the aperture establishing a fulcrum for the trammel on said beam, rotatable means on said trammel for engaging the beam on the other side from said fulcrum, said rotatable means having a cam surface establishing a pair of spaced substantial lines of contact with said beam and arranged by rotation to swing the trammel relative to said beam about said fulcrum.

9. In beam compasses, a trammel having a beam-receiving aperture, a beam positionable in the aperture, means on one side of the aperture establishing a fulcrum for the trammel on said beam, rotatable means on said trammel for engaging the beam on the other side from said fulcrum, said rotatable means having a cam surface establishing a pair of spaced substantial lines of contact with said beam and arranged by rotation to swing the trammel relative to said beam about said fulcrum, means for varying the spaced relation of the fulcrum and rotatable means to enable relative separation thereof to facilitate sliding of the trammel on the beam and for relatively closer positioning thereof for establishing a frictional engagement restricting relative sliding of the trammel on the beam.

10. In beam compasses, a trammel having a beam-receiving aperture, a beam positionable in the aperture, means on one side of the aperture establishing a fulcrum for the trammel on said beam comprising a first gripping member for the beam, rotatable means on said trammel for engaging the beam on the other side from said fulcrum comprising a second gripping member for the beam, said rotatable means having a cam surface establishing a pair of spaced substantial lines of contact with said beam and arranged by rotation to swing the trammel relative to said beam about said fulcrum, and means for mounting one of the beam-gripping members in the trammel for resilient yielding as the rotatable means is adjusted.

JOHN W. OEHRLI.
